REVOKING MECHANISM FOR WEFT
REPLENISHING LOOMSClifford Darwin, Worcester, Mass., assignor to
Crompton & Knowles Loom Works, Worcester,
Mass., a corporation of Massachusetts

Application August 4, 1939, Serial No. 288,412

5 Claims. (Cl. 139—231)

This invention relates to improvements in revoking mechanism for weft replenishing looms and it is the general object of the invention to provide mechanism by which revoking can be ac-

complished by a positive motion derived from a misplaced shuttle.

Weft replenishing mechanisms generally employ a transfer arm to which is pivoted a latch normally out of the path of a bunter on the reciprocating lay. When a transfer is called by weft exhaustion the latch is moved into the path of the bunter and as the lay moves forwardly a force transmitted through the latch depresses the transfer arm to insert a fresh bobbin into the depleted shuttle. If the shuttle should be misplaced as the result of a weak pick or rebounding it would not be in proper position to receive the fresh bobbin and a mechanism including a shuttle feeler acts to lower the support for the latch. By such an arrangement the latch falls by gravity away from the path of the bunter, but in high speed looms the time allowed to the latch to fall to bunter clearing position is so short that a transfer is not always revoked and a broken bobbin or shuttle may result. It is an important object of my present invention to provide a positive connection between the shuttle feeler and the latch operative during the first part at least of the descent of the latch to move the latter clear of the bunter path.

In a recently issued patent to Turner No. 2,162,290 there is shown a revoking mechanism including an arm which rises preparatory to transfer and sets the shuttle feeler in detecting position and also raises the transfer latch into the path of the bunter. The raising of the latch is effected by a lifter or setting mechanism which engages the under side of the latch. As shown in that patent revocation of a transfer effects lowering of the lifter but gravity is relied upon to depress the latch below the path of the bunter. It is a further object of my present invention to form the latch and lifter as shown in that patent with cooperating parts which become interrelated during the lifting of the latch to establish a temporary positive connection between the latch and the shuttle feeler. By reason of this positive connection the first part of any motion of the shuttle feeler derived from a misplaced shuttle is communicated positively to the latch. I prefer to make the interengaging parts separate during the latter part of the revoking motion, but this separation does not occur until the latch is below the path of the bunter. As a matter of convenience I make one of the interengaging

parts, preferably that carried by the latch, adjustable so that the amount and duration of the positive connection can be set for most efficient operation of the mechanism.

When moving to transfer position the latch swings around a pivot in an upward arcuate path and as shown in the aforesaid Turner patent the arm which carries the lifter also swings around a pivot. It is another object of my present invention to place the cooperating parts, one on the lifter and one on the latch, in such positions that their arcuate paths intersect to effect mutual engagement during upward motion of the latch. Although the lifter as set forth hereinafter moves in an arcuate path I do not deem this an essential relationship, since it is sufficient that the two co-acting parts move in intersecting paths.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a side elevation of a loom having a weft replenishing mechanism equipped with my improved revoker, parts being in section and the transerrer latch being shown in down or non-transferring position,

Fig. 2 is a view similar to Fig. 1 but with the latch raised to transfer position and with the positive connection established between the latch and the shuttle feeler,

Fig. 3 is a detailed rear elevation on an enlarged scale in the direction of arrow 3, Fig. 2, and

Figs. 4, 5 and 6 are diagrammatic views showing the manner in which the positive connection between the latch and shuttle feeler is established.

Referring to the drawing, I have shown a loom frame 10 having a lay 11 mounted on lay swords 12 driven by a connector 13 attached to the usual top or crank shaft not shown by means of which the lay is moved backwardly and forwardly, or to the right and left as viewed in Fig. 1. In Fig. 1 the lay is shown in its forward or front center position where transfer takes place. The lay is supported by and swings around rocker pins 15 in the usual manner.

A shuttle box 16 receives the shuttle S and a transfer bunter 17 extends forwardly from the lay for engagement with a transfer latch 18 normally down and below the path of bunter 17 under normal conditions as shown in Fig. 1. A transerrer arm 19 having a fixed pivot 20 is connected pivotally to a latch carrier 21 as at 22.

The transfer arm 19 is normally up as is well understood in bobbin changing mechanisms but can be depressed by engagement of the bunter 17 and latch 18 during forward motion of the lay.

5 The magazine M as shown herein provides two distinctive types of reserve bobbins indicated at W and W', respectively, and rocks about a fixed pivot 23 to place one or the other of the reserve bobbins under the transfer arm 19. It is not 10 believed necessary to give a description of the mechanism by which the magazine is rocked and reference may be had to the aforesaid Turner patent for further details of the magazine and the means by which it is rocked. I have also omitted 15 the selector mechanism by which the angular position of the magazine is determined. As shown in Fig. 1, however, I have shown the forward or left end of a normally stationary arm 32 which rises preparatory to a transfer from the 20 position shown in Fig. 1 to that shown in Fig. 2. It is deemed unnecessary to show and describe the means by which this arm is raised, since the mechanism is that shown in the aforesaid Turner patent and also used extensively in multicolor 25 shuttle changing looms.

A stand 60 held to the loomside by a bolt 61 may have its angular position varied by means of two adjusting screws 62 which when set cooperate with the bolt to hold the stand in rigid adjusted 30 position. The bracket carries stud 63 on which is mounted a carrier lever 64 having a horn 65 on which is secured the shuttle feeler 66. The latter may be formed as a rod with an enlarged head 67 for direct engagement with the shuttle should the 35 latter be misplaced during forward motion of the lay.

Depending from lever 64 is an arm 68 which is pivotally connected as at 69 to a rod head 70 adjustable on the upper end of a setting rod 71. 40 The lower end of this rod is adjustably connected to another rod head 72 from which depends a finger 73. This finger has a notch 74 in the lower end thereof above which is a flattened area 75 leading to a recessed inclined part 76. The bottom of finger 73 is connected by a light tension spring 77 to the lower end of a second finger 78 pivoted at its upper end as at 79 to the rod head 72. The two fingers are movable away from each other against the action of spring 77 and are 45 normally urged to move toward each other to have engagement with a stud 80 on arm 32. Stud 80 is normally located in the pocket 74 out of which it can move during the latter part of the upward motion of arm 32.

50 Extending upwardly from the arm 68 is a latch lifter or setter 85 adjustable vertically in the arm by a check nut 86. An adjustable stop screw 87 held in fixed position as shown in Fig. 1 limits upward motion of latch 18. Arm 64 has a small 55 finger 90 movable between and limited by front and back adjustable stop screws 91 and 92, respectively, carried in the stand 60.

In the operation of parts thus far described the lay normally reciprocates, causing the bunter 17 to traverse a path above the latch 18, and the latter together with the shuttle feeler will be in non-transferring position, that is, latch 18 will be down and shuttle feeler 66 will be forward, their positions determined by engagement of finger 90 with stop screw 92 as shown in Fig. 1. The arm 32 will be normally at rest and the stud 80 will be in the pocket 74. When transfer is to occur arm 32 will rise to lift rod 71 and therefore rock arm 64 in a clockwise direction. This has the effect 75 of moving the shuttle feeler 66 rearwardly or to

the right from the position of Fig. 1 to that of Fig. 2, and also causing rising of the lifter 85 against the under surface of the latch 18 to lift the latter to the position of Fig. 2 in the path of bunter 17. When the parts are set for transfer as just described and as shown in Fig. 2, a finger 90 will 5 engage stop screw 91, but arm 32 will continue to rise, thereby causing stud 80 to move out of the pocket 74 and assume a position along the flattened area 75 as shown in Fig. 2. These motions 10 attending the rising of arm 32 occur while the lay is in rear position and when completed set the loom for transfer, and it is while the parts are in the position shown in Fig. 2 that shuttle S enters the shuttle box. If the shuttle is properly 15 placed the bunter will engage the latch and a normal transfer will ensue. If, however, the shuttle is misplaced and projecting from the shuttle box the shuttle feeler will be moved forwardly and act through horn 65 to rock arm 64 20 in a counter-clockwise direction and thereby lower the lifter 85 against the relatively light resistance offered by the spring 77 which holds substantially parallel surfaces against the temporarily stationary stud 80. A resetting pin 93 for returning the 25 arm 64 to normal position may be as shown in the Turner patent but will be described in more detail hereinafter.

The parts thus far described of themselves form no part of my present invention except as pointed 30 out in the following description, and for a further description reference may be had to the patent already mentioned.

In carrying my invention into effect I provide the lifter with a forwardly extending finger 100 35 and also mount a plate 101 on the latch. This plate has a slot 102 through which extends a screw 103 tapped into the latch. The plate 101 may therefore be given any one of a plurality of adjusted 40 positions with respect to the latch. The lower part of the plate is bent horizontally to provide a shelf 105, see Fig. 3 which is spaced below the lower surface 106 of the latch 18. The latter therefore defines with the shelf a pocket proportioned to receive the finger 100. 45

During the lifting of arm 64 as already described the finger 100 will swing around the stud 63 and engage the under side of the latch 18. Continued upward motion of the finger 100 will rock the latch around the transfer arm carried 50 pivot 22. Because of the location of the pivots around which the finger 100 and the shelf 105 turn, these parts traverse intersecting paths.

As shown diagrammatically in Fig. 4 the finger 100 has just engaged surface 106 of the latch but 55 the latter has not yet started to move. In Fig. 5 the finger 100 has moved to a higher position and caused turning of the latch around its pivot to raise the shelf 105 to a position under the finger 100. Still further upward motion of the finger 60 100 to its final position reached when the parts are set for transfer, as shown in Fig. 6, will move the shelf 105 farther under the finger 100. By reason of the adjustment of the plate 101, the shelf 105 can be caused to move under the finger 65 100 before the latch reaches the path of the bunter 17, and the result of this adjustment is to require the shelf to remain under the finger whenever the latch is in position where it can engage the bunter. 70

Having in mind the previously described operation of revocation, it will be seen that during a normal transfer the latch will be able to move forwardly away from the finger 100 during descent of the transfer arm in a normal transfer. 75

Should the shuttle be misplaced, however, a rocking of arm 64 in a counter-clockwise direction as viewed in the drawing will move the finger 100 down by a positive force derived from the shuttle and transmitted through the shuttle feeler. During this downward motion the finger will engage the shelf 105 and exert a positive downward force on the latch which effectively moves the latter out of the path of the bunter. During the latter part of the revoking movement by the arm 64 the finger 100 and the shelf will become disengaged, but this does not occur until after the latch has been moved positively to a position out of the path of the bunter.

It is necessary to make provision for returning the arm 64 and shuttle feeler 66 to the normal position shown in Fig. 1 when a normal transfer occurs. This is done by means of a resetting pin 93 projecting forwardly from the lay for engagement with the horn 65. The pin and the plate 101 are set in such a way that forward motion of the latch during the normal transfer will move the shelf 105 to a position out of the arcuate path of the setter 100 before the pin 93 engages the horn 65. By this relationship the lifter or setting mechanism and the latch move out of force transmitting relationship with respect to each other before the resetting of arm 64 begins and as a result the latch 18 does not interfere with the return of the shuttle feeler to normal position.

The complete restoration of normal connections between the shuttle feeler and the lever 32 may be substantially the same as set forth in the aforesaid Turner patent and it is not thought necessary here to give any detailed description of the relationship of the stud 80 and the parts connected to the bottom of rod 71 other than to say that descent of lever 32 spreads the parts 73 and 78 because of the engagement of finger 90 with the stop screw 92, thereby permitting stud 80 to return to the notch 74, after which the mechanism is completely reset and ready for another replenishing operation.

From the foregoing it will be seen that I have provided a very simple means for lowering the latch when a transfer is revoked by a force derived from the misplaced shuttle and transmitted positively through the finger 100 and the shelf 105. It will also be seen that the positive transmission of force does not interfere with the forward motion of the latch during a normal transfer. In this connection I may say that in a normal transfer the shuttle feeler will be moved from its detecting back to its normal forward position before the latch becomes disengaged from the bunter, but this operation can occur because of the fact that the shelf 105 will move forwardly from a position under finger 100 during the first part of a normal transfer and arm 64 may therefore fall to its normal position without interfering with shelf 105. During the subsequent release of the latch by the bunter as the lay recedes the shelf 105 can fall freely with the latch without interference on the part of the finger 100 since the latter has already reached that part of its path which does not intersect the arcuate path of the shelf. The parts can therefore resume a position preparatory to another transfer upon the completion of a normal transfer.

Having thus described my invention it will be seen that changes and modifications may be made therein by those skilled in the art without departing from the spirit and scope of the invention.

and I do not wish to be limited to the details herein disclosed, but what I claim is:

1. In a weft replenishing loom having a trans-
ferrer arm and a lay with a bunter to actuate the
transferrer arm, a latch pivoted to the trans-
ferrer arm and normally out of the path of the
bunter, setting mechanism to move the latch an-
gularly into the path of the bunter, a pivotal sup-
port for the setting mechanism, a shuttle feeler
secured to the setting mechanism and movable by 10
the latter to shuttle detecting position when the
latch moves to transfer position, and two normally
disconnected parts one of which moves along a
given arcuate path with the setting mechanism
and the other of which moves along a curved path 15
with the latch, said parts moving along paths
which intersect as the setting mechanism moves
the latch to transfer position, said parts there-
upon having force transmitting relationship with
respect to each other, the shuttle feeler when en-
gaged by a misplaced shuttle moving the setting
mechanism and causing a force to be transmitted
through said parts to move the latch away from
the path of the bunter. 20

2. In a weft replenishing loom having a trans-
ferrer arm and a lay with a bunter to actuate the
transferrer arm, a latch pivoted to the trans-
ferrer arm and normally out of the path of the
bunter and movable in an arcuate path from
normal to transfer position setting mechanism 30
normally in non-transferring position, a pivotal
support for the setting mechanism, means to
move the setting mechanism to transfer position
along an arcuate path around said pivotal sup-
port preparatory to a weft replenishing opera-
tion, said setting mechanism when moving to
transfer position engaging the latch and mov-
ing the latter angularly into the path of the
bunter, a shuttle feeler moving with the setting
mechanism and moved by the latter to shuttle 35
detecting position when the setting mechanism
moves to transfer position, and means secured to
the latch movable in a curved path with said
latch toward transfer position, the paths of the
setting mechanism and said means being sepa-
rated when the setting means and latch are in
normal position, and the paths of the setting
mechanism and said means approaching each
other and overlapping as the latch moves to 40
ward transfer position to establish force trans-
mitting relationship between the setting mech-
anism and said means, the shuttle feeler when
moved by a misplaced shuttle causing the set-
ting mechanism to move from transfer toward 45
normal position and cause the latch to move
from transfer toward normal position by a force
transmitted positively through said means, the
setting mechanism and said means when return-
ing to normal position lying along parts of their 50
paths which are separated. 55

3. In a weft replenishing loom having a trans-
ferrer arm and a lay with a bunter to actuate the
transferrer arm, a latch pivoted to the trans-
ferrer arm and movable relatively to the latter
in a curved path and normally out of the path
of the bunter, setting mechanism normally dis-
connected from the latch and movable in a given
arcuate path toward said curved path of the 60
latch to engage and place the latter into the
path of the bunter, a shuttle feeler connected
to the setting mechanism to be moved to shuttle
detecting position when the latch is moved into
the path of the bunter by the setting mecha- 65
70
75

- nism; means carried by the latch normally disconnected from the setting mechanism to be moved angularly by the latch toward said given arcuate path of the setting mechanism into force transmitting relationship with respect to the setting mechanism during movement of the latch toward the path of the bunter, the bunter moving the latch to move said means and break said force transmitting relationship at a given time in a normal transferring operation; and means to initiate return of the setting mechanism to normal position after the force transmitting relationship has been interrupted during a normal transfer; movement of the shuttle 10 feeler by a misplaced shuttle when transfer is revoked causing the setting mechanism to move the latch away from the path of the bunter by a force transmitted through the first named means prior to said time.
5. In a weft replenishing loom having a trans-
ferrer arm and a reciprocating lay with a bunter
to actuate the trans-
ferrer arm, a latch pivoted to the trans-
ferrer arm and normally out of the path of the
bunter, setting mechanism moving along a given
arcuate path to engage and move the latch angularly
into the path of the bunter preparatory to a transferring operation of the loom, a shuttle 15 feeler moving with the setting mechanism and
moved thereby to shuttle detecting position when
the latch moves toward the path of the bunter,
means normally out of said given arcuate path
of the setting mechanism movable into said given
arcuate path by angular motion of the latch to-
ward the bunter path to establish force trans-
mitting relationship between the setting mech-
anism and the latch, motion of the latch by the
bunter during a normal transfer moving said
means to break the force transmitting relation-
ship between the setting mechanism and said
means at a given time in the loom cycle, and
other means acting subsequent to the breaking
of said force transmitting relationship during
the normal transfer to initiate movement of the
setting mechanism away from transfer position,
the shuttle feeler when moved by a misplaced
shuttle revoking the transfer and causing the
setting mechanism to move the latch away from
the path of the bunter by a force transmitted
through the first named means before said given
time. 10
5. In a weft replenishing loom having a trans-
ferrer arm and a reciprocating lay with a bunter
to actuate the trans-
ferrer arm, a latch pivoted to the trans-
ferrer arm and normally out of the path of the
bunter, setting mechanism normally
disconnected from the latch, a pivotal support
for the setting mechanism spaced from the axis
of the latch, said setting mechanism being mov-
able angularly to engage and move said latch 15
pivotally into the path of the bunter preparatory
to a transfer operation, a shuttle feeler secured
to the setting mechanism and movable by the
latter to shuttle detecting position when the
latch is moved into the path of the bunter by
said setting mechanism, two normally discon-
nected parts one of which moves angularly with
the setting mechanism and the other of which
moves angularly with the latch, said parts mov-
ing angularly into force transmitting relation by
30 motion of the latch caused by the setting mech-
anism, engagement of the latch by the bunter
during a normal transfer separating said parts
to break the force transmitting relationship at
a given time in the loom cycle, movement of the
shuttle feeler by a misplaced shuttle causing the
latch to move out of the path of the bunter and
thereby revoke transfer by a force transmitted
through said parts prior to the given time. 25
